UNITED STATES PATENT OFFICE.

CHARLES W. KIRSCH, OF STURGIS, MICHIGAN, ASSIGNOR TO KIRSCH MANUFACTURING CO., OF STURGIS, MICHIGAN, A CORPORATION OF MICHIGAN.

CURTAIN-FIXTURE.

1,281,023.

Specification of Letters Patent.

Patented Oct. 8, 1918.

Application filed October 2, 1917. Serial No. 194,352.

To all whom it may concern:

Be it known that I, CHARLES W. KIRSCH, citizen of the United States, residing at Sturgis, in the county of St. Joseph and State of Michigan, have invented certain new and useful Improvements in Curtain-Fixtures; and I do hereby declare the following to be a full, clear, and exact description of the invention, such as will enable others skilled 10 in the art to which it appertains to make and use the same.

This invention relates to improvements in curtain rods, and has for its particular object to provide a curtain rod so constructed and 15 arranged as to permit of the curtains being swung from a position parallel with the window sashes of a window, to a position substantially at right angles thereto and out of the direct path of air currents passing 20 into and out of such window when opened, and out of the way of a window-washer.

A particular object of the invention is to provide a curtain rod of this character which may be readily swung from one to another of its positions by merely engaging 25 the curtain or drape suspended therefrom and exerting a relatively light tension thereon so as to avoid the necessity of mounting a chair or ladder for the purpose of 30 operating the same.

A further object of the invention is to provide a curtain rod comprising two parts disposed in alinement with each other and having their ends opposed to each other in 35 close proximity contiguous to the portion of the window frame over which said rods are mounted, and which may be turned outwardly relatively to the window frame or the like so as to extend transversely thereto 40 and substantially parallel with each other.

A further object of the invention is to provide a curtain fixture of the character defined in the preceding paragraph which includes a bracket or support equipped with 45 means for yieldingly resisting the pivotal movement of the rod members and for yieldingly holding the same firmly at either limit of their pivotal movement.

A further object of the invention is to 50 provide a curtain rod of the type above set forth which when swung outwardly from its normal position to promote ventilation and permit ease of access to the window panes for washing the same, will throw the bodies

of the curtains or draperies suspended therefrom laterally away outwardly from the window opening for a distance equal, or substantially equal, to that separating the main portions of said curtains or draperies from the inner face of the window frame. 55

The invention includes fixtures for curtain rods adapted to receive a pair or a plurality of pairs of curtains or draperies, and consists in the features of construction and combinations of parts hereinafter fully described and particularly claimed. 60

In the accompanying drawings illustrating a suitable embodiment of the invention:

Figure —1— is a view in front elevation of a curtain-fixture comprising brackets or supports to each of which two curtain or drapery-supporting members are pivotally secured. 70

Fig. —2— is a top plan view of the same.

Fig. —3— is a top plan view of a fixture 75 including a pair of brackets and rods for supporting a single pair of curtains or draperies.

Fig. —4— is a fragmentary detail section on an enlarged scale on the line 4—4 of 80 Fig. —2—.

Fig. —5— is a fragmentary detail plan section on the line 5—5 of Figs. —1— and —6—.

Fig. —6— is a fragmentary detail vertical 85 section on the line 6—6 of Fig. —5—.

Fig. —7— is a fragmentary detail plan section on the line 7—7 of Fig. —8—.

Fig. —8— is a detail vertical section on the line 8—8 of Figs. —3— and —7—. 90

Fig. —9— is a fragmentary detail perspective view showing one of the outer ends of a curtain rod constituting a part of the fixture.

In warm weather it is obviously desirable, 95 in order that there may be no obstruction to air currents admitted through open windows in front of which curtains or draperies are hung, to dispose said curtains or draperies out of the path of such air currents not 100 only for the purpose of securing better ventilation, but also for the purpose of maintaining the curtains or draperies clean for a longer period of time. This has generally been accomplished by the employment of 105 hold-back fixtures disposed at the opposite sides of the window frame, or the like, for "hooking" back the lower end portions of

the curtains or draperies so as to keep them out of the path of the air currents. This, however, has proved relatively undesirable, and, where it is desired to open the upper 5 end or the entire length of the window opening, is entirely insufficient. The object of the present invention is, therefore, to provide means better adapted and more convenient to attain the desired results.

- 10 To this end I provide brackets each consisting of a plate 1 adapted to be secured to a window frame, or the like, at opposite sides of the opening therein, and which is equipped along its upper and lower edges respectively, with horizontally disposed flanges 2 and 3. The lower flange is provided along its outer edge with an upwardly extending lip 4 and a similarly extending lip 5 having an inclined edge 6 which terminates in a flat 15 shoulder 7 at the free edge of said lip 5, and which constitutes one end of an inclined shoulder 8 formed by means of a narrow flat strip of metal integral with the lip 5, and extending downwardly at an incline 20 from the shoulder 7 to the upper surface of the flange 3 contiguous to its juncture with the plate 1.

Passing through the flanges 2 and 3 at a point inwardly of the lips 4 and 5 is a pivot 30 pin 9 which also passes through the inner end of the arm 10 of a curtain rod member 11. The said curtain rod member consists, preferably, as shown in Fig. —9—, of a strip of metal C-shaped in cross-section, and 35 having openings in its side flanges contiguous to the end of the arm 10 thereof through which said pivot pin passes. A helical compression spring 12 bears upon the upper edge of said arm 10 and upon the lower 40 face of the flange 2, the same being coiled about the pivot pin 9 which is readily removable, as will be obvious. It will be noted that the outer edge portion of the flange 3 and more particularly the formations on said edge engage the rod at some 45 distance from its pivot and that the portion of the rod disposed above the body of the flange 3 does not rest upon the same at any time. This spaced support coacts with 50 the pivot pin and with the relatively widely spaced flanges of the rod through which the latter passes to increase the resistance of the rod to distortion under the influence of the weight of curtains or draperies suspended 55 from the same. This is further promoted to some extent by the pressure exerted by the spring 12.

At its other end each of the curtain-supporting members or rods 11 is provided with 60 a ferrule 13 telescopically mounted thereon and securely held in place by friction, and which is provided with a plurality of perforations 14 for the reception of pins or threads by means of which one end of the 65 hem of the curtain or drapery is secured

thereto to prevent it projecting from said end of said rod. The other end of the curtain or drapery-supporting member 11 or the arms 10 thereof is similarly provided with a ferrule 15 through which the 70 pivot pin 9 extends, and which is provided at one end with a sharp V-shaped projection 16 over which the hem of the curtain or drape is adapted to extend for holding the curtain in place at the pivoted end portion of said supporting member. 75

The arm 10 of the rod 11 is normally positioned between the inclined surface 6 of the lip 5 and the opposing side edge of the lip 4 so that it rests on said inclined edge 5 80 and not upon the flange 3 of the bracket. When in this position the main portion 11 of the supporting member will extend substantially parallel with the window sash, or the like. When it is desired to swing the curtain or drapery suspended from the rod 11 and its arm 10 out of the path of air currents, said curtain or drape is grasped by the hand and manipulated so as to cause the rod to swing on its pivot through an arc of substantially ninety degrees. In so doing the lower edge portion of the arm 10 of the rod must ride over the inclined surface 6 and shoulder 7 against the action of the spring 12 bearing down upon said rod and resisting 85 its vertical upward movement. After passing over the shoulder 7 the lower edge of the rod will ride upon the inclined surface 8 and will be held by the latter yieldingly in the new position. Said position is indicated in 90 dotted lines in Fig. —7—, and may be determined by a stop formation coacting with the surface 8 in the same manner as the lip 4 coacts with the inclined surface 6 of the lip 5 to prevent the rod from turning through 95 an arc in excess of ninety degrees. This is, however, not essential, but is desirable in some instances. In Fig. —7— I have, therefore, illustrated a lip 17 corresponding in 100 shape and function to the lip 4 at the forward or outer end of the flange 3 to coact with the inclined surface 8 to limit the pivotal movement of the rod and hold it yieldingly in the desired position. 105

My invention is also adapted for curtain fixtures adapted to support a plurality of pairs of curtains or draperies, as shown in Figs. —1—, —2—, —4—, —5— and —6—. In each of said figures I have shown brackets each equipped with means for pivotally securing thereto and supporting thereon one end of each of two curtain or drapery-supporting elements or rods corresponding to the element 11, shown in Figs. —3—, —7— and —8—. As shown in Fig. 115 —2—, the inner of said curtain-supporting rods or elements corresponds exactly with that shown in Figs. —3—, —7— and —8—, and is, therefore, indicated as to all parts, by the same reference characters. The outer 120 125 130

of the curtain-supporting elements 18, shown in Fig. —2—, is provided with an arm 19 of greater length than the arm 10 of the member 11. The said arm extends parallel with the arm 11 and is attached to a pivot pin 20 mounted in the bracket nearer the plate 1 than the pin 9 to which the arm 11 is pivotally secured. The flange 3 of the plate 1 is similarly provided with the lip 4 constituting a stop for limiting the pivotal movement of the arm 10 of the rod 11 in one direction, and which coacts with the inclined surface 6 of the lip 5 to hold said rod 10 firmly in position the same as in Figs. —3—, —7— and —8—. The plate 1 is equipped with a stop projection 21 for engaging the extreme outer end of the arm 19 of the rod and this coacts with the inclined surface 22 of a lip 23 corresponding in shape and function with the lip 5, and terminates in the inclined strip 24, corresponding in shape and function with the strip 8 of the lip 5. Provision is thus made for turning each of the several rods supported from the bracket outwardly to throw the draperies or curtains suspended therefrom out of the path of the air currents, and also in position to permit the windows to be readily washed. Obviously the rod 18 would have to be returned to its outer position before the rod 11 is turned to the same position. Provision will be made, as will be obvious, for similarly pivotally supporting rods in excess of two.

While I have shown the preferred embodiment of my invention in the accompanying drawings, it will be obvious, of course, that said embodiment may be changed and varied in details of construction without departing from the invention as defined in the appended claims.

It will be apparent that my invention is particularly adapted for use in connection with so-called "French windows" which swing on hinges similarly to doors and is also particularly adapted to windows in which a single sash extends the entire length and is dropped into the wall when it is desired to secure ventilation.

It will be noted that the pivots of the rods are disposed in close proximity to the window casing at the ends of the short arms thereof so that the longer arms are spaced from the inner face of said casing. When said rods are of ninety degrees the longer arms become separated from each other a distance equal to the space separating their pivots plus the combined lengths of the short arms and the curtains are thus disposed more completely out of the path of the drafts passing into and out of the open windows and also permit ample space between them to make cleaning of window panes more convenient. The proximity of the pivots to the window casing is also ad-

vantageous in that it permits the curtains and drapes to be extended to the inner face of the latter.

I claim as my invention:

1. A curtain fixture comprising a pair of brackets adapted to be mounted on a window casing contiguous to the inner side edges thereof, curtain rods each having a long and a short arm substantially perpendicular to each other pivotally connected at the ends of their short arms to said brackets, the ends of the long arms thereof normally opposed to each other substantially midway between the side edges of the window frame for supporting curtains or draperies at a distance from the window sashes, said rods adapted to be swung through an arc of substantially ninety degrees for causing the long arms thereof to swing laterally outwardly relatively to the window opening and out of the path of air currents passing through the window, the short arms thereof adapted to then extend substantially parallel with and in close proximity to the face of the window casing.

2. A curtain fixture comprising a pair of brackets adapted to be mounted on a window casing contiguous to the inner side edges thereof, curtain rods each having a long and a short arm substantially perpendicular to each other pivotally connected at the ends of their short arms to said brackets, the ends of the long arms thereof normally opposed to each other substantially midway between the side edges of the window frame for supporting curtains or draperies at a distance from the window sashes, said rods adapted to be swung through an arc of substantially ninety degrees for causing the long arms thereof to swing laterally outwardly relatively to the window opening and out of the path of air currents passing through the window, the short arms thereof adapted to then extend substantially parallel with and in close proximity to the face of the window casing, said bracket equipped with means for firmly retaining the rods in the respective aforesaid positions.

3. A curtain fixture comprising a pair of brackets adapted to be mounted on a window casing contiguous to the inner side edges thereof, curtain rods each having a long and a short arm substantially perpendicular to each other, said rods being flat and provided at their side edges with flanges provided with openings contiguous to the ends of the short arms of said rods, pivot pins on said brackets passing through the openings in said flanges, said pivot pins disposed in close proximity to the face of the window casing carrying said brackets, the ends of the long arms thereof normally opposed to each other substantially midway between the side edges of the window frame for supporting curtains or draperies at a

distance from the window sashes, said rods adapted to be swung through an arc of substantially ninety degrees for causing the long arms thereof to swing laterally outwardly relatively to the window opening and out of the path of air currents passing through the window, the short arms thereof adapted to then extend substantially parallel with and in close proximity to the face of the window casing.

4. A curtain fixture including a plate adapted to be mounted on a window casing and equipped with a vertically disposed pivot pin, a flange and a projection on said plate having openings for the passage of said pivot pin, a curtain rod through one end of which said pivot pin passes for pivotally connecting the same with said plate, an edge formation on said flange for engaging the lower edge of the rod at a distance from its pivot, and a spring on said pivot pin bearing upon the upper edge of said rod and said projection for holding the rod firmly engaged with said edge forma-

tion of said flange and prevent sagging of the main body of the rod carrying the draperies.

5. A curtain fixture comprising a pair of brackets mounted on the face of the window casing or the like, a pair of curtain rods each pivotally secured at one end to one of said brackets for permitting the same to swing horizontally through an arc approximating ninety degrees, a shoulder on the bracket for limiting the pivotal movement of said rod in one direction, a ridge presenting an inclined surface opposing said shoulder and together with the same forming a substantially V-shaped recess of less width at its bottom than said rod for holding the latter firmly in engagement with said shoulder, said rods when positioned to engage said shoulders of said brackets being disposed and firmly held in substantially accurate alignment and with their free ends opposed to each other.

CHARLES W. KIRSCH.
